UNITED STATES PATENT OFFICE.

WILLIAM W. MILLER, OF PHILADELPHIA, PENNSYLVANIA, ASSIGNOR TO
EUGENE IVINS, OF SAME PLACE.

DESIGN FOR A CAKE OR CRACKER.

SPECIFICATION forming part of Design No. 26,575, dated February 2, 1897.

Application filed December 8, 1896. Serial No. 614,975. Term of patent 31 years.

To all whom it may concern:

Be it known that I, WILLIAM W. MILLER, a citizen of the United States, residing in the city and county of Philadelphia and State of Pennsylvania, have invented and produced a new and original Design for Cakes and Similar Articles, of which the following is a specification, reference being had to the accompanying drawings, of which—

Figure 1 is a plan view of a cake, cracker, or biscuit, showing my design. Fig. 2 is a section on line $x x$, Fig. 1.

This design consists of a crescent a , from about the middle line of which on the concave edge of the crescent extend three points $b b b$, presenting the appearance of three points of a conventional star, and in or upon the side of the body of the crescent is a line or depression C , forming the outline of points

$d d$, which constitute, with the points $b b b$, 20 the form or outline of a complete conventional star S .

The leading features of my design are the crescent and the projecting star-points $b b b$, united to and projecting from the concave 25 edge of the crescent, and the lines forming the star-points d on or in the body of the crescent may be omitted.

Having thus described my design, I claim—

The design for a cake, or similar article, as 30 herein shown and described.

In testimony whereof I have hereunto affixed my signature in the presence of two subscribing witnesses.

WILLIAM W. MILLER.

Witnesses:

WALTER C. PUSEY,
JOSHUA PUSEY.
